INKING MECHANISM

Joseph Sinkovitz, Pittsburgh, Pa., assignor to
 Miller Printing Machinery Co., Pittsburgh, Pa.,
 a corporation of Pennsylvania

Application March 30, 1949, Serial No. 84,329

14 Claims. (Cl. 101—357)

1

This invention relates to inking mechanism, particularly inking mechanism for printing presses. It has to do with inking mechanism which is movable into and out of cooperative relationship with the form rollers of a printing press, such, for example, as inking mechanism of the so-called "rollaway" type.

Inking mechanism is well known which can be bodily removed or rolled away from a printing press with which the inking mechanism is adapted to be used to facilitate work on the press when the press is not being used for printing, as, for example, when a form is being made ready, and also to provide for cleaning and repair of parts of the press and inking mechanism. The form inking rollers are mounted in the press and the inking mechanism which delivers ink from the ink fountain to the form rollers is separated from the form rollers when it is moved away. The inking mechanism comprises an ink fountain and suitable means for working up the ink and delivering the worked up ink to the form rollers, which means may include an ink drum, a ductor roller or rollers between the ink fountain and the ink drum, a vibrator roller or rollers cooperating directly with the form rollers and an ink transfer roller or rollers between the ink drum and the vibrator roller or rollers.

It is frequently necessary when the inker is disposed in its inoperative position away from the press to remove the form rollers in order to gain access to portions of the press to be worked on. The form rollers are mounted in the press in position to ink the form during operation of the press. The working surfaces of the form rollers are either composition or rubber and, of course, are covered with ink. They cannot be set down on their working surfaces because the rollers would thereby be deformed and because anything coming in contact with the working surfaces of the form rollers would be smeared with ink. It has been necessary to specially provide a place to dispose the form rollers when they have been removed so that they are supported by their shafts with their working surfaces out of contact with the support. Moreover the form rollers are long and heavy, particularly in the larger sized presses, and it has generally been necessary for two men working together to remove the form rollers individually one after the other. When the form rollers are replaced they have to be replaced in similar fashion. Thus a very considerable amount of work has been required to remove and replace the form rollers in addition to the fact that it has been necessary

2

to specially provide a place to dispose the form rollers when removed from the press so that they will be supported by their shafts at the ends of the rollers instead of upon their working surfaces.

5 Inking mechanism has been devised, as disclosed in copending applications Serial Nos. 48,556 and 48,581, filed September 10, 1948, which is movable into and out of cooperative relationship with respect to the press, i. e., into and out 10 of position to deliver ink to the form rollers, and which may be so operated that when desired the form rollers may be automatically removed from the press and carried along with the inker. In such mechanism means are provided for engaging the form rollers and removing them from their supports or bearings when it is desired that the form rollers be carried along with the inker upon movement of the inker away from the press, such means being movable between operative and 15 inoperative positions relatively to the form rollers in a direction longitudinally of the press or generally in a plane normal to the axes of the form rollers. While such mechanism is satisfactory in use a problem incident to clearance between the 20 form roller shafts and the means for lifting the form rollers out of their bearings is presented which results in the form roller lifting means having shallow channels for carrying the form rollers with danger that the form rollers may 25 become accidentally dislodged from the channels.

30 I have devised a mechanism for the same purpose as the mechanisms of said copending applications but which obviates the problem incident to clearance above referred to and enables the 35 form roller lifting means to have yokes or sockets of any desired size, eliminating the danger of the form rollers becoming dislodged from the relatively shallow channels referred to. I provide for moving the form roller lifting or engaging means 40 between operative and inoperative positions relatively to the form rollers in a direction generally longitudinally of the form rollers or transversely of the inking mechanism. When the form roller engaging means are in inoperative position they 45 are offset longitudinally of the form rollers or laterally of the inking mechanism from the ends of the form roller shafts so that no problem of vertical clearance between the form roller engaging means and the form roller shafts is presented. Moreover, my structure is of relatively simple, rugged and foolproof design adapted to 50 withstand long usage without impairment of its efficiency.

I provide inking mechanism comprising supporting means, form roller means carried there-

by and removable therefrom, means for delivering ink to the form roller means, the ink delivering means being movable into and out of location adjacent the form roller means when carried by the supporting means, and means movable generally in the direction of the length of the form roller means to operative position to engage the form roller means and remove the same from the supporting means upon movement of the ink delivering means out of said location and to inoperative position wherein it has no effect on the form roller means upon movement of the ink delivering means out of said location. The inking mechanism may comprise generally parallel side frame members and the supporting means may be positioned between the general planes of the side frame members. The form roller engaging means may be movable between operative and inoperative positions transversely of the general planes of the side frame members. The means for delivering ink to the form roller means may be carried by the side frame members.

The means for engaging the form roller means may comprise opposed members movable generally in the direction of the length of the form rollers means or transversely of the general planes of the side frame members between operative and inoperative positions. The opposed members may move toward each other to their operative positions and away from each other to their inoperative positions. I preferably provide means connecting the opposed members for moving the same in opposite directions generally in the direction of the length of the form roller means between their operative and inoperative positions. I may employ operating means movable generally in the direction of the length of the form roller means for moving the form roller engaging means between operative and inoperative position.

I preferably employ turnable means turnable about an axis extending generally in the direction of the length of the form roller means, operating means movable generally in the direction of the length of the form roller means upon turning of the turnable means and connections between the operating means and the form roller engaging means whereby the latter are operated by the former. The turnable means may be carried by the side frame members and may be turnable about an axis extending generally transversely of the general planes of the side frame members. The turnable means may comprise a shaft rotatably carried by the side frame members, and cam means may be provided on the shaft cooperating with means on the opposed form roller engaging members whereby said members are operated by the cam means upon turning of the shaft. Guiding means are preferably provided for the opposed members insuring substantially rectilinear movement thereof and preventing turning thereof with the shaft. Springs means may be provided urging the opposed members to inoperative position, the cam means moving them to operative position against the action of the spring means upon turning of the turnable means.

Other details, object and advantages of the invention will become apparent as the following description of a present preferred embodiment thereof proceeds.

In the accompanying drawings I have shown a present preferred embodiment of the invention in which

Figure 1 is an elevational view of inking mechanism and a portion of a printing press with which the inking mechanism is cooperable, the inking mechanism being shown in operative position with respect to the press;

Figure 2 is a view similar to Figure 1 showing the inking mechanism in angularly displaced position ready to be moved away from the press while leaving the form rollers in position in the press;

Figure 3 is a view similar to Figures 1 and 2 showing the inking mechanism removed from the press with the form rollers remaining in position in the press;

Figure 4 is a view similar to Figure 2 but showing the form rollers removed from their bearings and supported by the inking mechanism in position to move away from the press along with the inking mechanism;

Figure 5 is a fragmentary plan view to enlarged scale of a portion of the mechanism showing the form roller engaging means in operative position relatively to the form rollers;

Figure 6 is a vertical longitudinal cross-sectional view taken on the line VI—VI of Figure 5; and

Figure 7 is a view similar to Figure 5 showing the form roller engaging means in inoperative position relatively to the form rollers.

Referring now more particularly to the drawings, there is shown a printing press designated generally by reference numeral 2 which may be of conventional flat bed and cylinder type and which may operate in normal manner in printing. Since the invention is concerned only with the inking mechanism the remainder of the press is not shown. The press has adjacent opposite sides thereof and extending longitudinally of the press in parallel relation bars 3 each carrying brackets 4, the brackets 4 being arranged in opposed pairs as shown in Figure 5. There are as many pairs of brackets 4 as there are form rollers in the press. Each bracket 4 is slidable along the bar 3 which carries it so as to assume a desired adjusted position on the bar and is fastened in such position by a set screw 5.

Each bracket 4 has a portion 6 projecting inwardly of the press from the bar 3 carrying the bracket and which carries at its inner end an upwardly open form roller bearing 7 vertically adjustable by an adjusting screw 8. The bearings 7 are thus disposed in transversely aligned pairs as shown in Figure 5, each being adapted to have a form roller shaft portion to be carried thereby disposed therein by generally downward movement and removed therefrom by generally upward movement.

There are shown two form rollers 9. Any desired number of form rollers may be employed, one or more. Each form roller has an enlarged central or working portion 10, necks 11 at both ends of the portion 10 and shaft portions 12 at the ends of the roller connected with the necks 11, the shaft portions 12 being, when the form rollers are in use, journaled in the bearings 7. Each shaft portion 12 extends outwardly beyond the outer edge of the corresponding bearing 7 as shown in Figure 5. The press bed which carries the type form moves under and in contact with the bottoms of the portions 10 of the form rollers, the form rollers thus inking the form. Ink is delivered to the form rollers by ink delivering means now to be described.

The inking mechanism comprises a frame having opposed frame members 13 which extend in

generally vertical planes parallel to each other. The frame members 13 are suitably fastened together by cross members not shown. Journalized in the frame members 13 is a shaft 14. Adjacent opposite ends of the shaft 14 and disposed inside the respective frame members 13 are pinions 15 which are keyed to the shaft 14. The press frame 2 has an extension 16 which comprises opposed portions extending longitudinally of the press beneath the pinions 15, each such portion having fastened to its upper surface an upwardly facing rack 17 with which one of the pinions 15 meshes, the inker frame comprising the frame members 13 and the mechanism carried thereby being partially supported by the press frame extension 16 through the racks 17. As will presently appear the inker frame may be bodily angularly displaced about the axis of the shaft 14.

The opposed portions of the press frame extension 16 also have tracks 18 and each of the inker frame members 13 carries a roller 19 adapted during movement of the inker toward and away from the press, as will be presently explained, to ride on one of the tracks 18. At the right-hand end of each track 18, viewing Figures 1, 2, 3 and 4, there is a track extension member 20 which is vertically movable and which when in its uppermost position has its upper surface at the level of the upper surface of the corresponding track 18 and in longitudinal alignment therewith so as in effect to form a short extension of the track. Each extension member 20 has a sleeve 21 projecting downwardly therefrom through which passes a bolt 22 having a head 23. Each member 20 has a socket 24 receiving the head 23 of the corresponding bolt 22, upward movement of the member 20 being limited by engagement of the bottom of the socket 24 with the under surface of the bolt head 23. Each bolt 22 and sleeve 21 are disposed within a bore 25 in the press frame extension 16 and each bolt 22 is screwed into the press frame extension. A compression coil spring 26 is confined in the bottom of the bore and presses upwardly against the bottom surface of the sleeve 21 so as normally to maintain the member 20 in its uppermost position as shown in Figures 2, 3 and 4. The springs 26 are strong enough to hold the members 20 in their uppermost positions when the rollers 19 and the mechanism connected therewith are supported by the members 20 as shown in Figures 2 and 4.

Journalized in the inker frame in a transverse shaft 27 to one end of which is fastened by a pin 28 a handle 29 for turning the shaft. Adjacent its opposite ends and within the inker frame members 13 the shaft 27 carries eccentrics 30. The press frame 2 has extensions 31 each disposed above one of the eccentrics 30 having a vertically oriented tapped hole into which is threaded a bolt 32 having a head 33, a nut 34 being adapted to be threaded onto each bolt 32 and turned up against the corresponding extension 31 to maintain the bolt in adjusted position. Each extension 31 is counterbored at 35 to provide clearance for the bolt head 33 upon vertical adjustment of the bolt. When the inker is in operative position relatively to the press each of the eccentrics 30 is adapted to engage the bottom surface of the corresponding bolt head 33. But at the same time the respective rollers 19 are disposed upon the track extensions 20. With the parts thus disposed turning of the handle 29 causes rotation of the shaft 27 and of the eccentrics 30. Since the eccentrics 30 engage the lower surfaces of the bolt

heads 33 and since the bolts 32 are fixedly positioned in the press frame extensions 31 turning of the eccentrics 30 causes angular displacement of the inker frame in the clockwise direction viewing Figure 1, such angular displacement being accompanied by downward depression of the track extension 20 by the rollers 19 which are disposed thereupon as shown in Figure 1. When the inker frame has been thus angularly displaced about the axis of the shaft 14 the inker is in operative relationship with respect to the press and the ink delivering means, presently to be described, are in position to deliver ink to the form rollers 9.

The ink delivering means comprises an ink fountain 36 having a fountain roll 37 for delivering ink from the ink fountain in usual manner. The fountain roll 37 is keyed to a shaft 38 disposed generally about the shaft 14. There is provided the usual ink drum 39 and a doctor roller 40 for transferring ink from the fountain roll 37 to the ink drum 39. Ink on the ink drum 39 is worked up by rollers 41 and 42, the latter transferring ink to the vibrator roller 43 which in turn seats in the saddle between the two form rollers 9 and transfers the ink to the form rollers. The ink transferring and working up functions may be performed in conventional manner and the invention is not dependent upon any particular arrangement of ink delivering means. It is sufficient to point out that when the inker is in operative position relatively to the press as shown in Figure 1 the vibrator rollers 43 seats in the saddle between the form rollers 9 and delivers ink thereto.

With the parts in operative position as shown in Figure 1, when it is desired to roll the inker away from the press the handle 29 is operated to turn the shaft 27 through approximately 180° which in turn rotates the eccentrics 30 through a similar angle so that the high points of the eccentrics are disposed downwardly relatively to the axis of the shaft 27 as shown in Figures 2, 3 and 4. Such turning of the shaft 27 is accompanied by upward movement of the track extensions 20 under the action of the compression coil springs 26, the members 20 being stopped when their upper surfaces are in alignment with the upper surfaces of the tracks 18 by the bolt heads 23 as above explained. But upward movement of the members 20 causes constant upward movement of the rollers 19 which at the time rest upon the members 20, and such upward movement of the rollers 19 in turn causes angular displacement of the inker about the axis of the shaft 14 from the position shown in Figure 1 to the position shown in Figures 2 and 4. Such angular displacement of the inker raises the vibrator roller 43 out of contact with the form rollers 9 and so that its lowermost point is above the uppermost points of the form rollers 9, thus providing for movement of the inker toward the left away from the press without interference between the vibrator roller and the form rollers. Movement of the inker away from the press is accomplished by turning the shaft 14 by means presently to be described. Since the pinions 15 are keyed to the shaft 14 and mesh with the stationary racks 17 turning of the shaft 14 in the counterclockwise direction viewing Figure 1 causes the pinions 15 to turn relatively to the racks 17 and hence the inker frame and everything carried thereby is bodily linearly displaced toward the left. During such displacement of the inker the rollers 19 ride upon the

tracks 18. The inker is shown in position spaced from the press in Figure 3.

When it is desired to return the inker to operative position the shaft 14 is turned in the clockwise direction until the inker assumes the position of Figures 2 and 4 whereupon the shaft 21 is turned through approximately 180° to cause the eccentric 30 to angularly displace the inker back to the position of Figure 1 with the vibrator roller 43 in engagement with the form rollers 9 so as to deliver ink thereto.

Extending through the inker frame from side to side and journaled in the generally parallel side frame members 13 is an element shown as being in the form of a shaft 44 constituting guide 15 means as will presently appear. The shaft 44 projects outwardly at both sides of the inker 15 and has fastened thereto at each side a knob 45 for turning the shaft. The knobs 45 may be pinned to the shaft 44. The pin for pinning one 20 of the knobs 45 to the shaft 44 is shown at 46. The pin 46 projects outwardly from the knob at one side to serve as a stop member to limit the amplitude of turning movement of the shaft 44. Projecting from the side frame member 13 at 25 the side of the inker at which the pin 46 is located are two stop pins 47 disposed in the path of movement of the projecting portion of the pin 46 upon turning of the shaft 44. The shaft 44 is turnable between a position as shown in Figure 5 in which the projecting portion of the pin 46 engages one of the stop pins 47 and a 30 position as shown in Figure 7 in which the projecting portion of the pin 46 engages the other of the stop pins 47. Fixed to the shaft 44 adjacent the respective ends thereof and, if desired, integral with the knobs 45 are cams 48 having inclined faces as shown in Figures 5 and 7 and which turn with the shaft 44.

Disposed adjacent the respective ends of the 40 form rollers 9 are opposed members 49 which are movable between the operative position shown in Figure 5 and the inoperative position shown in Figure 7 and are for the purpose when operative of lifting the form rollers from their bearings 7 upon movement of the inker out of inking position. Each of the members 49 has a socket 50 for one end of each form roller, the sockets being of ample size to prevent accidental dislodgement of the form rollers therefrom. Each member 49 50 has a hub 51 through which the shaft 44 extends and a cam 52 adapted to engage and cooperate with the cam 48 and constituting operating means for the member 49. The hubs 51 are in guided relationship with the shaft 44 so that the members 49 are guided thereby for movement axially of the shaft 44. Each of the members 49 carries a guide pin 53 guidably received within a drilled guide opening 54 in one of the side frame members 13. The guide pin 53 insures that the member 49 carrying it will 55 take of substantial rectilinear movement and will not turn with the shaft 44.

Fastened to the shaft 44 by set screws 55 are collars 56. Between each collar 56 and the adjacent hub 51 is a compression coil spring 57. The springs 57 resiliently urge the members 49 outwardly or toward the inside faces of the side frame members 13. When the shaft 44 is in the position of Figure 7 with the inclined faces of 70 the cams 48 and 52 lying in face-to-face engagement with each other the members 49 are pushed by the springs 57 outwardly against the inner faces of the side frame members 13 as shown in Figure 7. When the members 49 are in that posi-

tion they are inoperative with respect to the form rollers and upon movement of the inker out of inking position they have no effect on the form rollers but move past the ends of the form rollers. When the shaft 44 is turned by one of the knobs 45 the cams 48 force the members 49 inwardly against the action of the springs 57 so that when the shaft 44 has turned through approximately 180° from the position of Figure 7 to the position of Figure 5 the members 49 are in the operative position shown in Figure 5. With the members 49 in that position they engage and lift the form rollers out of the bearings 7 when the inker moves out of inking position. Each end of each form roller is received in one of the sockets 50 which is of ample size to retain it against accidental displacement therefrom. Thus, when the members 49 are in their operative positions as shown in Figure 5, instead of the inker being moved away from the press leaving the form rollers in position in the press the form rollers are carried away along with the inker. When the inker is returned to operative position the form rollers come back with it and are replaced in their bearings 7 as shown in Figure 1.

If it is desired to roll the inker away from the press while leaving the form rollers in their bearings 7, the shaft 44 is turned to the position of Figure 7 to move the members 49 to their inoperative positions. When the members 49 are thus positioned and the inker is angularly displaced to the position shown in Figure 2 the members 49 simply rise without carrying the form rollers with them, passing outside the ends of the form roller shafts. Figure 2 shows the inker in angularly displaced position ready to be rolled away with the members 49 in inoperative position and Figure 3 shows the inker in rolled away position leaving the form rollers 9 in place in their bearings 7. Figures 2 and 4 correspond to each other except that in Figure 4 the members 49 are in operative position and have lifted the form rollers up out of their bearings 7 so that 35 when the inker is rolled away to the left the form rollers will go with the inker, leaving the bearings 7 empty and hence the space therebetween available for work.

Outside the inker frame the shaft 14 has a pin 58 passing therethrough and projecting outwardly therefrom at both sides. Mounted for sliding movement along the shaft 14 is a handle 59 having at its outer portion a hub 60 slotted at 61 and having at its inner portion and integral therewith a gear 62. An idler pinion 63 rotatably mounted on a stub shaft 64 meshes with a gear 65 fixed to the shaft 38. The handle 59 may be moved axially of the shaft 14 so that either the slots 61 embrace the pin 58 or the gear 62 meshes 60 with the pinion 63. When the handle 59 is in position with the slots 61 embracing the pin 58 and the handle is operated to turn about the axis of the shaft 14 the shaft 14 is turned, resulting in movement of the inker toward or away from the press, depending upon the direction of turning of the handle. When the gear 62 is in mesh with the pinion 63 and the handle is turned it causes turning of the fountain roll 37 through the gear 65.

While I have shown and described a present preferred embodiment of the invention it is to be distinctly understood that the invention is not limited thereto but may be otherwise variously embodied within the scope of the following 75 claims.

I claim:

1. Inking mechanism comprising generally parallel side frame members, supporting means positioned between the general planes of the side frame members, form roller means carried by the supporting means and removable therefrom, means carried by the side frame members for delivering ink to the form roller means, the ink delivering means being movable into and out of location adjacent the form roller means when carried by the supporting means, opposed members respectively carried by the side frame members movable generally toward each other transversely of the general planes of the side frame members to operative positions to engage the form roller means and remove the same from the supporting means upon movement of the ink delivering means out of said location and to inoperative position wherein they have no effect on the form roller means upon movement of the ink delivering means out of said location, a shaft rotatably carried by the side frame members to turn about an axis extending generally transversely of the general planes of the side frame members, cam means on the shaft and means on the opposed members engaging the cam means whereby the opposed members are operated by the cam means upon turning of the shaft.

2. Inking mechanism comprising generally parallel side frame members, supporting means positioned between the general planes of the side frame members, form roller means carried by the supporting means and removable therefrom, means carried by the side frame members for delivering ink to the form roller means, the ink delivering means being movable into and out of location adjacent the form roller means when carried by the supporting means, turnable means carried by the side frame members turnable about an axis extending generally transversely of the general planes of the side frame members, opposed members respectively having openings through which the turnable means passes movable generally toward each other transversely of the general planes of the side frame members to operative position to engage the form roller means and remove the same from the supporting means upon movement of the ink delivering means out of said location and to inoperative position wherein they have no effect on the form roller means upon movement of the ink delivering means out of said location, cam means on the turnable means and means on the opposed members engaging the cam means whereby the opposed members are operated by the cam means upon turning of the turnable means.

3. Inking mechanism comprising generally parallel side frame members, supporting means positioned between the general planes of the side frame members, form roller means carried by the supporting means and removable therefrom, means carried by the side frame members for delivering ink to the form roller means, the ink delivering means being movable into and out of location adjacent the form roller means when carried by the supporting means, a shaft rotatably carried by the side frame members to turn about an axis extending generally transversely of the general planes of the side frame members, opposed members respectively having hubs through which the shaft passes movable generally along the shaft toward each other transversely of the general planes of the side frame members to operative position to engage the form roller means and remove the same from the support-

ing means upon movement of the ink delivering means out of said location and to inoperative position wherein they have no effect on the form roller means upon movement of the ink delivering means out of said location, guiding means for the opposed members insuring substantially rectilinear movement thereof and preventing turning thereof with the shaft, cam means on the shaft and means on the opposed members engaging the cam means whereby the opposed members are operated by the cam means upon turning of the shaft.

4. Inking mechanism comprising generally parallel side frame members, supporting means positioned between the general planes of the side frame members, form roller means carried by the supporting means and removable therefrom, means carried by the side frame members for delivering ink to the form roller means, the ink delivering means being movable into and out of location adjacent the form roller means when carried by the supporting means, a shaft rotatably carried by the side frame members to turn about an axis extending generally transversely of the general planes of the side frame members, opposed members respectively having hubs through which the shaft passes movable generally along the shaft toward each other transversely of the general planes of the side frame members to operative position to engage the form roller means and remove the same from the supporting means upon movement of the ink delivering means out of said location and to inoperative position wherein they have no effect on the form roller means upon movement of the ink delivering means out of said location, guiding means for the opposed members insuring substantially rectilinear movement thereof and preventing turning thereof with the shaft, spring means urging the opposed members to inoperative position, cam means on the shaft and means on the opposed members engaging the cam means whereby the opposed members are moved by the cam means to operative position against the action of the spring means upon turning of the shaft.

5. Inking mechanism comprising supporting means, form roller means carried thereby and removable therefrom, means for delivering ink to the form roller means, the ink delivering means being movable into and out of location adjacent the form roller means when carried by the supporting means, guide means extending generally in the direction of the length of the form roller means and means mounted on and movable generally along the guide means to operative position to engage the form roller means and remove the same from the supporting means upon movement of the ink delivering means out of said location and to inoperative position wherein it has no effect on the form roller means upon movement of the ink delivering means out of said location.

6. Inking mechanism comprising generally parallel side frame members, supporting means positioned between the general planes of the side frame members, form roller means carried by the supporting means and removable therefrom, means for delivering ink to the form roller means, the ink delivering means being movable into and out of location adjacent the form roller means when carried by the supporting means, guide means extending generally transversely of the general planes of the side frame members and means mounted on and movable generally along the guide means to operative position to

engage the form roller means and remove the same from the supporting means upon movement of the ink delivering means out of said location and to inoperative position wherein it has no effect on the form roller means upon movement of the ink delivering means out of said location.

7. Inking mechanism comprising generally parallel side frame members, supporting means positioned between the general planes of the side frame members, form roller means carried by the supporting means and removable therefrom, means carried by the side frame members for delivering ink to the form roller means, the ink delivering means being movable into and out of location adjacent the form roller means when carried by the supporting means, guide means extending generally transversely of the general planes of the side frame members and opposed members mounted on and movable generally along the guide means to operative position to engage the form roller means and remove the same from the supporting means upon movement of the ink delivering means out of said location and to inoperative position wherein they have no effect on the form roller means upon movement of the ink delivering means out of said location.

8. Inking mechanism comprising supporting means, form roller means carried thereby and removable therefrom, means for delivering ink to the form roller means, the ink delivering means being movable into and out of location adjacent the form roller means when carried by the supporting means, guide means extending generally in the direction of the length of the form roller means and opposed members mounted on and movable generally along the guide means toward each other to operative position to engage the form roller means and remove the same from the supporting means upon movement of the ink delivering means out of said location and movable generally along the guide means away from each other to inoperative position wherein they have no effect on the form roller means upon movement of the ink delivering means out of said location.

9. Inking mechanism comprising supporting means, form roller means carried thereby and removable therefrom, means for delivering ink to the form roller means, the ink delivering means being movable into and out of location adjacent the form roller means when carried by the supporting means, guide means, opposed members mounted on and movable generally along the guide means to operative position to engage the form roller means and remove the same from the supporting means upon movement of the ink delivering means out of said location and to inoperative position wherein they have no effect on the form roller means upon movement of the ink delivering means out of said location and means connecting the opposed members for moving the same in opposite directions generally along the guide means between said operative and inoperative positions.

10. Inking mechanism comprising supporting means, form roller means carried thereby and removable therefrom, means for delivering ink to the form roller means, the ink delivering means being movable into and out of location adjacent the form roller means when carried by the supporting means, means movable to operative position to engage the form roller means and remove the same from the supporting means upon movement of the ink delivering means out of said location and movable to inoperative position

wherein it has no effect on the form roller means upon movement of the ink delivering means out of said location, guide means extending generally in the direction of the length of the form roller means and operating means mounted on and movable generally along the guide means for moving the form roller engaging means between said operative and inoperative positions.

11. Inking mechanism comprising supporting means, form roller means carried thereby and removable therefrom, means for delivering ink to the form roller means, the ink delivering means being movable into and out of location adjacent the form roller means when carried by the supporting means, means movable to operative position to engage the form roller means and remove the same from the supporting means upon movement of the ink delivering means out of said location and movable to inoperative position wherein it has no effect on the form roller means upon movement of the ink delivering means out of said location, an element extending generally in the direction of the length of the form roller means, turnable means mounted for turning movement about the axis of said element, operating means mounted for movement generally in the direction of the length of the form roller means upon turning of the turnable means and connections between the operating means and the form roller engaging means whereby the latter are operated by the former.

12. Inking mechanism comprising supporting means, form roller means carried thereby and removable therefrom, means for delivering ink to the form roller means, the ink delivering means being movable into and out of location adjacent the form roller means when carried by the supporting means, opposed members movable generally toward each other generally in the direction of the length of the form roller means to operative position to engage the form roller means and remove the same from the supporting means upon movement of the ink delivering means out of said location and movable generally away from each other generally in the direction of the length of the form roller means to inoperative position wherein they have no effect on the form roller means upon movement of the ink delivering means out of said location, turnable means turnable about an axis extending generally in the direction of the length of the form roller means and cam means between the turnable means and the opposed members whereby the latter are operated by the former.

13. Inking mechanism comprising generally parallel side frame members, supporting means positioned between the general planes of the side frame members, form roller means carried by the supporting means and removable therefrom, means carried by the side frame members for delivering ink to the form roller means, the ink delivering means being movable into and out of location adjacent the form roller means when carried by the supporting means, guide means extending generally transversely of the general planes of the side frame members, opposed members mounted on and movable generally along the guide means to operative position to engage the form roller means and remove the same from the supporting means upon movement of the ink delivering means out of said location and to inoperative position wherein they have no effect on the form roller means upon movement of the ink delivering means out of said location, turnable means turnable about an axis extending

generally transversely of the general planes of the side frame members and connections between the turnable means and the opposed members whereby the latter are operated by the former.

14. Inking mechanism comprising generally parallel side frame members, supporting means positioned between the general planes of the side frame members, form roller means carried by the supporting means and removable therefrom, means carried by the side frame members for delivering ink to the form roller means, the ink delivering means being movable into and out of location adjacent the form roller means when carried by the supporting means, opposed members respectively carried by the side frame members and mounted for movement generally toward each other transversely of the general planes of the side frame members to operative position to engage the form roller means and remove the same from the supporting means upon movement of the ink delivering means out of said location

5 and to inoperative position wherein they have no effect on the form roller means upon movement of the ink delivering means out of said location, turnable means carried by the side frame members turnable about an axis extending generally transversely of the general planes of the side frame members and connections between the turnable means and the opposed members whereby the latter are operated by the former.

10 JOSEPH SINKOVITZ.
